US00D525127S

(12) **United States Design Patent** (10) **Patent No.:** **US D525,127 S**
Cogley et al. (45) **Date of Patent:** **** Jul. 18, 2006**

(54) **SUSCEPTOR RING**

(75) Inventors: **Paul Andrew Cogley**, Chicago, IL (US); **Derek Joseph Romeo**, Evanston, IL (US); **Joseph R. Brooks**, Chicago, IL (US)

(73) Assignee: **Kraft Foods Holdings, Inc.**, Northfield, IL (US)

(**) Term: **14 Years**

(21) Appl. No.: **29/200,575**

(22) Filed: **Mar. 1, 2004**

(51) **LOC (8) Cl.** **09-07**

(52) **U.S. Cl.** **D9/456**

(58) **Field of Classification Search** D9/651, D9/546, 499, 456, 454, 449, 447, 445, 439, D9/438, 435, 434; D7/629, 542, 511, 510, D7/392, 392.1, 391; D34/39; D3/323; D12/211, D12/207, 204; 99/DIG. 14; 426/243; 413/8; 301/40.3, 37.101, 108.1-5, 104

See application file for complete search history.
